Primary Examiner — Kevin K Rudzinski

(74) Attorney, Agent, or Firm — Edwin Tarver

(57) **CLAIM**

The ornamental design for a garment with an integrated backpack, as shown and described.

DESCRIPTION

FIG. 1 illustrates a perspective view of a garment with an integrated backpack;

FIG. 2 illustrates a back view thereof;

FIG. 3 illustrates a front view thereof;

FIG. 4 illustrates a left side view thereof;

FIG. 5 illustrates a left side section view thereof, taken along line 5-5 in FIG. 2;

FIG. 6 illustrates a right side view thereof;

FIG. 7 illustrates a top view thereof;

FIG. 8 illustrates a bottom view thereof; and,

FIG. 9 illustrates a perspective view of the garment reversed with the unclaimed subject matter on the inside of the backpack.

The broken lines showing the garment illustrate environmental structure and form no part of the claimed design.

1 Claim, 8 Drawing Sheets
